CHRISTMAS ORNAMENT

Richard Goonen, Chicago, Ill.

Application May 21, 1956, Serial No. 41,578

Term of patent 14 years

(Cl. D29—1)

Figure 1 is a fragmentary front perspective view of a Christmas ornament showing my new design;

Figure 2 is a front elevational view thereof; and

Figure 3 is a side sectional view taken in the vertical plane of line 3—3 of Figure 2.

The dominant features of the design reside in the portions shown in full lines.

The broken-line illustration of the nativity scene in Fig. 1 is for illustrative purposes only.

I claim:

The ornamental design for a Christmas ornament, substantially as shown and described.
